UNITED STATES PATENT OFFICE.

RUBIN ROSENTHAL, OF NEW YORK, N. Y.

RING AND SETTING.

1,412,810.

Specification of Letters Patent. Patented Apr. 11, 1922.

Application filed September 28, 1921. Serial No. 503,778.

To all whom it may concern:

Be it known that I, RUBIN ROSENTHAL, a citizen of the United States, and a resident of the city of New York, borough of 5 Manhattan, in the county of New York and State of New York, have invented a new and Improved Ring and Setting, of which the following is a full, clear, and exact description.

10 This invention relates to rings and settings therefor, and has for an object to provide an improved construction wherein the usual form and contour of the ring is preserved, and at the same time, a readily 15 removable ornament is carried by the ring.

Another object of the invention is to provide a ring and setting structure wherein the setting is firmly held in place by spring pressed fasteners.

20 A still further object of the invention is to provide a ring and setting wherein the setting is built up of a number of parts and locked in place by a resilient catch positioned interior of the ring, while the ornament 25 is arranged exteriorly thereof.

In the accompanying drawings:

Figure 1 is a top plan view of a ring disclosing one embodiment of the invention;

30 Figure 2 is a sectional view through Figure 1, approximately on the line 2—2;

Figure 3 is a horizontal sectional view through Figure 2 on the line 3—3;

Figure 4 is a section view through Figure 2, approximately on the line 4—4;

35 Figure 5 is a detail perspective view on a reduced scale of the ring, with a setting and fastening means therefor removed;

Figure 6 is an inverted perspective view 40 of the ornament forming part of the setting;

Figure 7 is a perspective view of an enamel plate and stud, disclosing certain features of the invention; and

45 Figure 8 is a perspective view of the locking spring shown in Figure 3.

Referring to the accompanying drawing by numerals, 1 indicates a ring body provided with what may be termed a head 2, which is formed with a depressional cavity 5 3 exteriorly, and a depressional cavity 4 40 interiorly. By forming the parts in this manner, a central web 5 is produced which is preferably thin, and which is preferably 45 cut away at a number of points 6. By cutting away the web 5, as stated, openings 55 are presented for the locking studs 7 and

8 projecting from the ornament 9, as hereinafter fully described. The shape of the recess or cavity 3 has been shown in the drawings as octagon, but it is understood 60 that it may be round or any desired shape without departing from the spirit of the invention.

A metallic plate 10 is formed to fit into the cavity 3, as shown in Figure 2; said 65 plate having a threaded stud 11 and having a coating 12 of enamel on the opposite side of the stud 11. This enamel may be of any color to properly set off the ornament 9. It is of course understood that the ornament 70 9 may be any desired ornament and is provided with two studs 7 and 8, which when in use project through apertures 13 and 14 in the plate 10 and enamel 12, so as to be 75 engaged by the locking spring 15. This locking spring is provided with four arms 80 16, each arm having a gripping face 17, which is adapted to engage the studs 7 and 8. These studs are preferably enlarged at the ends and somewhat rounded so that 85 they may freely enter the space between each arm 16, and then permit the jaws to move toward each other overlapping the enlarged ends, as indicated in Figure 4. This will positively lock the ornament 9 85 in place, so that the arrangement will permit a ready removal when the studs 7 and 8 have been pressed in a reverse direction.

The plate 10 is held rigidly in place by a threaded bore 18, positioned centrally 90 of the spring 15, whereby said spring in respect to the stud 11, acts as a clamping nut. When all the parts have been assembled and fitted into the ring, the parts

will appear as shown in Figures 1 and 2 95 and the top of the ornament 9 will usually

be flush with the top of the head 2 and it will be noted from Figure 1 that the enamel 100 12 shows through or around the ornament 9, so as to produce a more pleasing appearance.

It will be noted also that the gripping action of the spring 15 in respect to the studs 7 and 8, not only acts as means for holding the ornament 9 in place, but acts as means for preventing the

105 spring 15 from unscrewing or backing off the threaded stud 11. Whenever it is desired to remove the ornament 9 for any

purpose, as for instance, to provide a different form of ornament, an instrument is 110

pressed against the ends of the studs 7 and 8 to force them through the jaws 17.

As soon as they have been released from the jaws 17, the ornament may be readily lifted off and a new one substituted by merely placing the same in position and 5 forcing the same into interlocked relationship with the spring 15. In case it should be desirable to change the color of enamel 12, the spring 15 is unscrewed from the stud 11 and plate 10 removed and a new 10 plate substituted which carries the proper color of enamel.

I claim:

1. A ring and setting comprising a ring body and head formed with inner and outer 15 cavities with a web therebetween, said web having a central aperture and a plurality of side apertures, an ornamental plate having a stud extending through said central aperture, an ornament pressing on said 20 plate having studs extending through said side apertures, and means engaging all of said studs for locking the same against removal.
2. A ring and setting comprising a ring 25 body formed with a head having an inner and outer cavity with a web arranged therebetween, said web being provided with a

plurality of apertures, an ornament positioned in said cavity, having studs projecting through said apertures, and a locking 30 spring member locking said ornament in place, said locking spring member being formed with a pair of resilient jaws for each of said studs, said locking spring member being located in said inner cavity. 35

3. A ring and setting comprising a ring body formed with a head having an inner and outer cavity with a web arranged therebetween, said web having a central aperture and a plurality of side apertures, an ornamental plate arranged in the outer cavity, 40 said plate having a threaded stud projecting through the central aperture in said web, an ornament fitting against said ornamental plate and provided with a plurality of studs, said studs extending through said side apertures in said web, and a combined nut and locking spring arranged in the inner cavity and screwed onto the stud projecting from the ornamental plate, and resiliently gripping the studs projecting from 45 said ornament. 50

RUBIN ROSENTHAL.
